INVENTOR. *C. Bradford*,
ATTORNEY.

UNITED STATES PATENT OFFICE.

ISRAEL HOGELAND, OF INDIANAPOLIS, INDIANA, ASSIGNOR OF ONE-HALF
TO GEORGE P. ANDERSON, OF SAME PLACE.

LIFTING-JACK.

SPECIFICATION forming part of Letters Patent No. 325,411, dated September 1, 1885.

Application filed April 7, 1885. (No model.)

To all whom it may concern:

Be it known that I, ISRAEL HOGELAND, of the city of Indianapolis, county of Marion, and State of Indiana, have invented certain new and useful Improvements in Lifting-Jacks, of which the following is a specification.

Generally, the object of my said invention is the same as that for which Letters Patent of the United States No. 259,393, dated June 13, 1882, were granted.

It consists in a rearrangement and simplification of the parts constituting said lifting-jack, and in certain new features, the principal ones of which are the forming of the storage-cylinder within the vertically-moving stem of the jack instead of outside and separate therefrom, a new construction of valves between the storage and supporting cylinders and means of operating the same, a connection between the rack-bar and lever-supports which permits them to be revolved about the jack, and the means of applying the lever to the head or block which engages with the rack-bar. These features as well as the general construction of the jack will now be fully described.

Referring to the accompanying drawings, which are made a part hereof, and on which similar letters of reference indicate similar parts, Figure 1 is a side elevation of a jack embodying my said invention; Fig. 2, a central vertical section of the same on the dotted line 2-2 in Fig. 3; Fig. 3, a horizontal sectional view looking downwardly from the dotted line 3-3 in Figs. 1 and 2; Fig. 4, a detail view on an enlarged scale similar to a portion of Fig. 2; Fig. 5, a horizontal sectional view on the same scale as Fig. 4, looking downwardly from the dotted line 5-5 in Figs. 2 and 4; and Fig. 6, a detail view showing the head or block D and adjacent parts.

In said drawings, the portions marked A represent the main cylinder of the jack; B, the piston, which is hollow, and also forms the storage-cylinder for the fluid; C, the rack-bar; D, a toothed block or head which engages with said rack-bar; E, a lever for operating the

same, and F a bracket-like support for the lever.

The cylinder A is mounted in a base, A', and supports the other portions of the jack. It is hollow, as shown, thus providing a receptacle for the fluid as it is drawn from the storage-cylinder in the upward movement of the jack and supports the upwardly-moving portions, as will be presently more fully described.

The piston B is tubular, as shown, and has a head, B', upon its upper end, which engages with the load to be raised. It is provided at the lower end with a stuffing-box and valve. The stuffing-box is of the ordinary construction and is easily understood. The valve consists of an orifice through the stuffing-box, and a rod or stem, B'', passing through said orifice, having its sides flattened or grooved to permit the liquid to pass by it. Upon the upper end of the stuffing-box is a cap-nut, b'', through which are ports leading into the storage-cylinder. Inside said cap-nut and passing through said stem is a pin, b', and between said pin and the upper end of the stuffing-box is arranged a spiral spring, b'', by which said stem is held up so that its lower end or head, b, is kept in contact with the lower end of the stuffing-box. The operation is, when the piston B is raised during the operation of the jack, that the suction in the cylinder A will pull down and open the valve and permit a portion of the liquid contained within the storage-cylinder to pass into said cylinder A. When the upward stroke is completed and the piston B is released from the force of the lifting-lever, the spring b'' will return the valve to its former position, closing the orifice, and thus the piston is supported in raised position by the fluid which has been drawn from the storage-cylinder, and this operation is repeated continually until the load has been raised to the height desired. Directly above the stem B'' of the valve, and in contact therewith, is arranged the rod B', which extends up to the upper end of the jack, and has a head, b', thereon. Its lower end is screw-threaded and enters the cap-nut b'', passing through said

cap-nut, and coming in contact with the stem B^2 of the valve, as before stated. When it is desired to lower the jack, this rod is turned by means of its head b' , which is housed in the head B' of the piston, and thus forces the stem B^2 of the valve down and its head out of contact with the under side of the stuffing-box, leaving a free passage-way from the cylinder A through the openings alongside the said stem and through the ports in the cap-nut into the storage-cylinder, thus permitting the return of the fluid from said cylinder A to said storage-cylinder, and allowing the piston to descend, the block or head D having first, of course, been removed from engagement with the rack-bar C. The head b' has a set-nut or projecting portion, b^6 , and is arranged closer to one side than the other of the head B' . Thus said projecting portion will pass one side of said head, but will come in contact with and be stopped by the other, whereby the movement of said head, the rod B^3 , and the valve, so far as operated thereby, will be limited.

25 The rack-bar C is mounted upon the piston B between the head B' and a collar, c , and extends down alongside the main cylinder A, between the sides of the bracket-like support F, in position to engage with the head or block D.

30 The block or head D is toothed correspondingly to the rack-bar and engages therewith. It rests upon the inner or cam-faced end of the lever E, between the wings of the bracket-like support F. It is provided with open extended sides d , which surround the pivot e of the lever, and is thereby held from being removed from position, and is, by reason of the large size of the openings in said sides d , permitted to be raised up and thrown over, so as to be out of engagement with the rack-bar. This head has a portion which extends out horizontally when in position for use, and forms a face, d' , against which the cam-face of the lever works.

45 The lever E is mounted on a pivot, e , which extends through and rests in inclined slots in the wings of the bracket-like support, and is provided with a cam-face which comes in contact with and operates the block or head D.

50 The bracket-like support F is provided with inclined slots or openings f for the pivot e of the lever E, similar to those shown and described in the aforementioned Letters Patent. 55 The support is provided with bands $f' f^2 f^3$, which extend around the main portion A of the jack, and said support is thus rendered easily revoluble thereon, thus enabling the operator to work from any side of the jack that 60 suits his convenience, the rack-bar C being also revolvably mounted on the piston B. An annular groove (see Fig. 2) is formed in the upper portion of the main cylinder A, and a set-screw, f^4 , set in the adjacent portion of 65 the support, enters this groove and prevents

any endwise movement of said support on said cylinder.

Having thus fully described my said invention, what I claim as new, and desire to secure by Letters Patent, is—

70 1. In a lifting-jack, the combination of a hollow cylinder mounted upon a base, a hollow piston, which also serves as a storage-cylinder, mounted in said cylinder, said hollow piston having a rack-bar secured thereon, and said cylinder having a lever and ratchet-faced block mounted on a bracket thereon, which engages with said rack-bar, a valve in the lower end of the hollow piston, which opens therefrom into the hollow cylinder, and a fluid 75 within said hollow cylinders, which passes from one to the other through said valve as said jack is operated, whereby said piston can be supported in elevated position after being elevated by said lever and rack-bar, substantially as set forth.

80 2. The combination, in a lifting-jack, of the cylinder A, a hollow piston, B, mounted therein, means of raising said piston, and a valve in the bottom of said piston, consisting of a stem, B^2 , passing through an opening in the stuffing-box, with a pin, b^4 , through its upper end, and a head upon its lower end, with the spring b^5 interposed between said pin and the upper end of said stuffing-box, said rod having its sides flattened to permit the passage of a fluid between said cylinders, substantially as set forth.

85 3. The combination, in a lifting-jack, of the cylinder A, hollow piston B, having a valve 90 in its lower end, a nut, b^2 , arranged above said valve, and a screw-threaded rod extending from said nut to the top of said piston, whereby said valve may be forced down, and thus opened and held in open position, substantially as set forth.

95 4. The combination, in a lifting-jack, of the main cylinder A, the combined piston and storage-cylinder B, having a valve in its lower end and a lifting-head on its upper end, a 100 bracket-like support, F, mounted upon said cylinder A, a rack-bar, C, mounted on the piston B, a rack block or head, D, and a lever, E, mounted on said bracket-like support, all substantially as shown and specified.

105 5. The combination, in a lifting-jack, of two cylinders, one arranged within the other, a bracket-like support upon the lower cylinder, the rack-bar upon the upper cylinder, a cam-faced lever mounted in said bracket-like support, and a ratchet-faced block or head engaging with said rack-bar, and having an overhanging face, with which the cam-face of said lever may engage, whereby said cam-faced lever is adapted to raise said block when 110 operated, substantially as shown and specified.

115 6. The combination, in a lifting-jack, of two cylinders, one mounted within the other, a valve in the lower end of the inner cylinder, the upper end of said valve being covered by 120

a cap-nut, ports through said cap-nut, and a screw-rod passing through said cap-nut for forcing said valve open, substantially as shown and specified.

5 7. The combination of the cylinder A, the hollow piston B, a valve in its lower end, a screw-rod, B³, for forcing and holding said valve open, a projection, b⁶, on the head of said rod, and a stop with which it will come

in contact for limiting its movement, substantially as set forth.

In witness whereof I have hereunto set my hand and seal, at Indianapolis, Indiana, this 3d day of April, A. D. 1885.

ISRAEL HOGELAND. [L. S.]

In presence of—

C. BRADFORD,

CHARLES L. THURBER.
